Primary Examiner — Daniel J Domino(74) *Attorney, Agent, or Firm* — Alston & Bird LLP(57) **CLAIM**

We claim the ornamental design for a display screen with animated graphical user interface, as shown and described.

DESCRIPTION

FIG. 1 is a front view of a first image showing a display screen with animated graphical user interface showing the new design;

FIG. 2 is a second image thereof;

FIG. 3 is a third image thereof;

FIG. 4 is a second embodiment showing front view of a first image of a display screen with animated graphical user interface showing the new design;

FIG. 5 is a second image thereof; and,

FIG. 6 is a third image thereof.

The outermost broken line perimeter illustrates a display screen, or the like or portion thereof and forms no part of the claimed design. All other broken lines illustrate features of a display screen with animated graphical user interface that form no part of the claimed design.

The appearance of the animated graphical user interface transitions sequentially between the images shown in FIGS. 1-3 in the first embodiment and the images shown in FIGS. 4-6 in the second embodiment. The process or period in which one image transitions to another forms no part of the claimed design.
